UNITED STATES PATENT OFFICE.

GEORGE F. GUNDLACH, OF NEW YORK, N. Y.

TOBACCO-PIPE.

1,359,986.

Specification of Letters Patent. Patented Nov. 23, 1920.

Application filed February 12, 1920. Serial No. 358,233.

To all whom it may concern:

Be it known that I, GEORGE F. GUNDLACH, a citizen of the United States, residing at 1412 Franklin Avenue, New York, county 5 of New York, and State of New York, have invented certain new and useful Improvements in Tobacco-Pipes, fully described and represented in the following specification and the accompanying drawings, forming a 10 part of the same.

This invention relates to a device applied to the bottom of a pipe-bowl to prevent the nicotine from passing into the bore of the pipe-stem and to facilitate the loosening up 15 of the tobacco in the bottom of the bowl when required.

In this invention the bottom of the pipe-bowl is formed with a chamber larger than the bowl with a shoulder between the two. 20 A removable plate is fitted to the said shoulder and clamped against the same by a plug fitted snugly into the chamber, and special means are provided for preventing the access of tobacco dust or nicotine from the 25 bowl to the pipe-stem.

The construction will be understood by reference to the annexed drawing, in which Figure 1 is a longitudinal section of a pipe provided with the improvement; Fig. 2 is a 30 perspective view of the plug from the bottom of the bowl; Fig. 3 is a plan of the bowl; Fig. 4 is a plan of the removable plate at the bottom of the bowl; and Fig. 5 is a cylindrical strainer to fit below such 35 plate. Fig. 6 shows the edge of the plate *d*.

a designates the bowl of the pipe in which the tobacco is placed with a chamber *b* at the bottom forming an annular shoulder *a'* to which a plate *d* is removably fitted and perforated with a hole *d'* in the center. 40

The plate is held snugly against the shoulder by a plug *c* fitted to press into the chamber *b* and having a recess or pocket *f* upon its upper side to catch the tobacco dust, 45 ashes and nicotine which pass through the hole in the plate *d*.

A groove *h* is formed around the periphery of the plug at the side of the recess *f*, and holes *e* are extended from the groove 50 *h* into the recess.

The pipe-stem *g* has its bore *h'* extended into connection with the groove *h* so that

when smoking the pipe the smoke is drawn through the hole *b'*, the holes *e* and the groove *h*.

55

An annular screen *i* is inserted in a shallow socket *f'* in the recess *f* between the plate *d* and the bottom of the recess, thus encircling the hole *b'* and screening out from the tobacco smoke any dust or ashes 60 which passes through the hole and which might foul the bore *h'*. The socket *f'* holds the screen central in the recess.

To loosen up the tobacco when it has settled in the bowl *a*, a spring-pin *m* is inserted through the plug and the screen *i* in line with the hole *b'*. 65

A spring *j* holds the pin normally in the recess, but when the tobacco requires loosening the pin is pressed upward by its head-piece *n*, forcing it through the hole *b'* and pushing away the tobacco over said hole, as indicated by the lines *d''*. 70

When it is desired to clean out the recess in the bottom plug and to remove and clean 75 the circular screen *i*, the plug is simply drawn from the chamber *b*, being pulled out by a flange *c'* around its margin, thus making all its inner parts accessible and permitting the plate *d* also to be removed from 80 the bottom of the bowl for cleaning.

The plug may obviously be screwed into the socket if preferred.

My construction is very advantageous as it is efficient in separating nicotine and dust 85 from the smoke, and the parts can all be readily separated for cleansing.

Having thus set forth the nature of the invention what is claimed herein is:

1. A tobacco pipe having a chamber at 90 the bottom larger than the bowl with shoulder between the two, a removable plate perforated in the center and fitted to such shoulder, a removable bottom plug fitted to such chamber and clamping the plate 95 against the said shoulder, and having a depressed central recess, a strainer fitted to the recess around the hole in the plate, a spring-pin movable at pleasure through the plug and the hole in the plate to loosen the 100 tobacco in the bowl and a connection from the pipe-stem to the said recess, the whole arranged and operated substantially as set forth.

2. A tobacco pipe having a chamber at the bottom larger than the bowl with shoulder between the two, a removable plate perforated in the center and fitted to such shoulder, a removable bottom plug fitted to such chamber and clamping the plate against the said shoulder, the plug having a groove

around its periphery communicating with the bore of the pipe-stem and holes extended from the groove into the recess of the plug, ¹⁰ substantially as set forth.

In testimony whereof I have hereunto set my hand.

GEORGE F. GUNDLACH.
